[57] CLAIM

The ornamental design for a support stand for a computer, substantially as shown and described.

DESCRIPTION

FIG. 1 is a front perspective view of a support stand for a computer showing our new design;

FIG. 2 is a front elevational view on a reduced scale;

FIG. 3 is a top plan view thereof;

FIG. 4 is a bottom plan view thereof;

FIG. 5 is a right side elevational view thereof, the left

side elevational view being a mirror image thereto; and

FIG. 6 is a rear elevational view thereof.
